PALETTE

William A. Sillman and Ilon M. Sillman,
New York, N. Y.

Application September 16, 1940, Serial No. 357,058

1 Claim. (Cl. 41—5)

This invention relates to improvements in artist's palettes and the like.

Present-day requirements in the field of the painting art and the like favors the use of a palette having the same color tone as the canvas or other ground upon which the work is executed. For example, if the color tone of the canvas is silvery-gray or white, then the palette should be possessed of the same color tone. Furthermore, the palette should be substantially non-porous or non-absorbent, have a good balance and easy to keep clean.

Heretofore, wooden palettes were chiefly employed by painters, particularly since the brown color of the wooden palette was in keeping with the color tone of the canvas employed at that time. It has been stated that brown palettes suited painters before impressionism and is practically of no value to the modernist whom it can only lead into error necessitating needless corrections, since in painting on a gray or a white ground as modern painters do, and if a brown colored palette is used, the color values must be translated. Due to the opposing tone value of the brown palette, proper or correct working on white or gray grounds becomes difficult because the tone value of the brown palette visually influences the tone of the paint pigment on the palette and makes it appear different from what it will when applied to the white ground of the paper or canvas.

The wooden palette on account of being porous is difficult to keep clean as the oil in the paint is absorbed into the wood, leaving the dry and hardened pigment on the surface of the palette necessitating a scraping operation to remove the same unless a paint remover is employed it is practically impossible to leave a thoroughly clean-surfaced palette.

It is, therefore, an object of the present invention to provide a practical and efficient transparent palette for artists and like persons which presents the same color tone as that of the ground of the canvas or other device upon which the work is to be executed.

It is a further object of the present invention to provide a transparent palette having a sheet element incorporated therein or therewith to facilitate the mixing of the paints with regard to their correct tone values and colors and with respect to the color tone of the device to be painted.

It is yet another object of the present invention to provide a transparent palette to which the aforesaid sheet element may be readily applied and maintained in applied position.

Still a further object of the present invention is to provide a transparent non-porous palette made of plastic or unbreakable material.

The above and other objects and advantageous features of the invention and the means for their attainment will be more apparent from the following detailed description, taken in connection with the accompanying drawing, illustrating some embodiments of which the invention may be realized, and in which

Fig. 1 is a plan view (partly broken away) of an artist's palette embodying the invention in one of its practical forms;

Fig. 2 is a plan view (partly broken away) of another form of artist's palette incorporating the invention.

Figs. 3—6 are typical transverse sections taken on either of Fig. 1 or Fig. 2;

Fig. 7 is a transverse section of a palette in a further modified form.

Referring now to the drawing more in detail, Figs. 1 and 2 disclose the palette as having an upper transparent sheet or plate 10, a lower plate or sheet 11 and a relatively thin flexible sheet 12 which may be interposed between plates 10 and 11. Fig. 1 shows the palette in one of its most conventional shapes having the thumb opening 13 and recess 14, while Fig. 2 shows the palette in a less conventional form, similarly having a thumb opening 15 and recess 16.

Other than their differences in shape, the constructions of the exemplified embodiments of the invention of Figs. 1 and 2 may be identical as typified in Figs. 3 to 6.

Transparent plate 10 is preferably made of substantially unbreakable material such as plastic composition or so-called unbreakable glass. One of the materials found very suitable for the purpose intended comprises an organic plastic, for example, a polymerized derivation of methacrylic acid, or methyl acrylate plastic. This material is very much lighter than glass, is flexible, nonbreakable, strong and durable and absorbs very little moisture. Furthermore, this plastic material offers resistance to most chemicals and oxidation, is free from bubbles and other flaws or defects and when abraded does not leave a permanently marred surface, and its surface is of such a nature as to be self-polishing; its surface tension is such that matter will not readily adhere to it. This plastic material is highly transparent and has very good light-transmitting or light-conducting qualities or properties.

In the forms shown in Figs. 3, 5 and 6, the bottom plate 18, 32 or 28 may be made of the

same material as that from which plate 10 is made. The flexible sheet 12 may be made of paper or any other suitable material, the tone color of which is similar to that of the ground of the canvas or other device (not shown) upon which the paint work is executed. This sheet is arranged or disposed below the transparent plate 10 and is a valuable aid in obtaining the correct tone values and colors in relation to the object being painted. If, for example, the canvas ground is white then a sheet 12 is selected having a white tone color; or, if the ground of the canvas to be painted is burnt sienna then the color tone of the flexible sheet should be burnt sienna. A sheet having a neutral gray tone color can be used for most purposes making it considerably more adaptable for color blending than the conventional dark wooden palette.

In Figs. 3-7, the numerals 17, 22, 25, 27 and 30, respectively, correspond in nomenclature to numeral 10, and numerals 18, 23, 32 and 28, respectively, correspond in nomenclature to numeral 11, of Figs. 1 and 2. Plates 17, 22, 25, 27 and 30 are made of the same material as plate 10.

In Fig. 3, each of plates 17 and 18 have marginal flanges 17', 18' at one end and are hinged together at their other ends by hinge 19. A space 33 is thereby provided to accommodate sheet 12. A conventional spring latch 20 secured to plate 18 lockingly engages plate 17. By manipulating latch 20 the plates 17, 18 may be swung apart about hinge 19 to insert or remove sheet 12.

Fig. 4 discloses a single plate having the spaced portions 22, 23 joined integrally at one of the ends 21 of the plate, the other end of the plate having the mouth 24 through which the sheet 12 may be inserted or withdrawn. A stop (not shown) may be provided at mouth 24 to prevent sheet 12 from falling out of space 24.

Fig. 5 shows plate 25 as having the marginal or peripheral flange 26 and a closure plate 32 for retaining sheet 12 between plates 25 and 32. The inner face of flange 26 is preferably bevelled to insure a tight fit between it and closure plate 32.

Fig. 6 shows transparent plate 27 and closure plate 28 as being secured together by interlocking ridges 29, 34.

In Fig. 7 the sheet 12 is secured to plate 30 by means of tongues, clamps or tapes 31.

From the foregoing it can be readily seen that there has been provided a palette comprising two transparent plates made of organic plastic material with a flat non-transparent member therebetween and having a uniform color to simulate the color of an artist's canvas, the non-transparent member being positioned between the two transparent plates so that the color of the non-transparent member is visible through either transparent member, any suitable means or instrumentality being provided for maintaining the transparent plates together with the non-transparent member therebetween. Thus, the non-transparent element lends its color to either transparent member whereby the effects of pigments mixed on the surface of either transparent member are determined with respect to their expected effect upon the artist's canvas, since the non-transparent element is related to the canvas.

As many possible embodiments may be made of the invention within the scope thereof, and as many changes might be made in the embodiments above set forth, it is to be understood that all matter hereinbefore set forth or shown in the accompanying drawing is to be interpreted as illustrative and not in a limiting sense.

Having thus described the invention, what is claimed as new and desired to be secured by Letters Patent, is

A palette comprising two transparent plates made of substantially non-absorbent organic plastic material, and a flat non-transparent member having a uniform color to simulate the color of an artist's canvas and positioned therebetween, the color of said member being visible through either transparent member and lending its color thereto whereby the non-transparent member is related to said canvas and the effect of pigments mixed on the surface of the transparent member are determined with respect to their expected effect upon an artist's canvas, and means for securing said plates together with said member therebetween.
